UNITED STATES PATENT OFFICE.

CHARLES B. FRENCH, OF KINGSTON, PENNSYLVANIA.

PNEUMATIC HAMMER.

986,160.

Specification of Letters Patent.

Patented Mar. 7, 1911.

Application filed April 28, 1909. Serial No. 492,710.

To all whom it may concern:

Be it known that I, CHARLES B. FRENCH, a citizen of the United States, residing at Kingston, in the county of Luzerne and 5 State of Pennsylvania, have invented a certain new and useful Improvement in Pneumatic Hammers, of which the following is a specification.

The invention relates to hammers operated by fluid pressure, and is intended more especially for service in cutting rivets and bolts in railroad and bridge work and analogous operations requiring quick heavy blows.

15 The object of the invention is to provide a simply constructed and operated hammer which may be easily directed to the work and will deliver the sharp heavy blow required.

20 The invention consists in certain novel features and details of construction and arrangement by which the above objects are attained, to be hereinafter described.

25 The accompanying drawings form a part of this specification and show the invention as it has been carried out in practice, for cutting off the heads of rivets in railway repair work.

Figure 1 is a plan view of the hammer 30 mounted upon a car or truck. Fig. 2 is a corresponding side elevation. Fig. 3 is a vertical transverse section, partly in elevation with a portion broken away, the section being through the center of the yoke.

35 Similar letters of reference indicate the same parts in all the figures.

As adapted for railway work, a truck or car A is employed mounted on wheels A¹ running on the rails A² and provided with 40 transverse ways A³ A³ on which travels a carriage B moving along the ways as required by a screw C held against axial movement and engaged in a nut, soon to be described, beneath the carriage. The screw 45 is rotated by a crank C¹ on an inclined shaft C², through the medium of beveled gears C³ C⁴ on the shaft and screw.

On the carriage is a pivotally mounted yoke C⁵ having bearings in its arms for 50 trunnions D¹ on the hammer cylinder D, on

which the cylinder may be turned to the desired vertical angle; the pivotal connection of the yoke to the carriage provides the required horizontal swing, and by moving the carriage on its ways the cylinder may be 55 pointed in any direction within its range.

The yoke C⁵ comprises the substantially parallel vertical portions in which the trunnions are mounted and the horizontal portion c⁵ through which passes the pivot c⁶, 60 the lower end of which is passed through the top member of the carriage B and this latter has the depending portion b⁵ which is threaded and constitutes a nut in which the screw C is engaged.

L is a motor having a shaft L¹ carrying on each of its overhung ends a sheave or narrow drum L² around which are taken one or more turns of a cable N, secured at its ends. By rotating the shaft in one direction or the other the car A on which the motor is mounted may be moved along the rails A² as the work progresses. The motor may be of any ordinary or approved type and is shown as receiving air from the chest 70 D⁴ through hose connections L³ L⁴ from ports, not shown, controlled by a handlever L⁵ and valve-stem L⁶ through a valve, not shown; any suitable arrangement of valve and ports will serve, as will be understood 75 80 without complete illustration.

I claim:—

In a hammer of the character set forth, a truck, ways thereon disposed transversely of the truck, a carriage movable on said 85 ways, a pivotally mounted yoke, a vertical pivot therefor carried by said carriage and on which it is free to swivel, said yoke having bearings, a ram cylinder having trunnions mounted in said bearings, means 90 for moving the carriage transversely of the truck, and means on the truck for moving the same in the direction of its length.

In testimony that I claim the invention above set forth I affix my signature, in presence of two witnesses.

CHARLES B. FRENCH.
